TIME-CONTROLLED SWITCH

Application filed December 20, 1926. Serial No. 156,018.

This invention relates to the class of switches and pertains particularly to a time controlled switch.

The primary object of this invention is the provision, in a manner as hereinafter set forth, of a time controlled switch for use in connection with electric current supply lines to households, stores, or other places where electric current is consumed, designed 10 to be set in operation after the insertion of a coin, and so adjusted as to run to maintain the circuits closed for a predetermined period of time.

Another object of the invention is to provide, in a manner as hereinafter set forth, in connection with a coin operated controlled switch, novel means whereby an electric circuit may be broken by a time mechanism after the elapse of a predetermined period 20 of time.

A further object of the invention is the provision, in a manner as hereinafter set forth, of a coin controlled electric switch of simple construction, positive operation, and 25 comparatively inexpensive to manufacture and install.

Other important objects and advantages of the invention will appear as the description of the same progresses, and the invention will be best understood from the consideration of the following detailed description taken in connection with the accompanying drawings, forming a part of this specification, with the understanding, however, that 35 the invention is not confined to any strict conformity with the showing of the drawings, but may be changed or modified so long as such changes or modifications mark no material departure from the salient features of the invention, as set forth in the appended claims.

In the drawings:

Figure 1 is a longitudinal sectional view through the casing of the structure taken 45 on a plane parallel with the front side thereof, showing the mechanism within the casing in front elevation;

Figure 2 is a longitudinal section taken through the casing of the structure in a plane 50 at right angles to the front and rear walls,

showing the operating mechanism therein in top plan;

Figure 3 is an enlarged detailed side elevation of a portion of the mechanism, parts thereof being broken away and in section; 55

Figure 4 is a transverse section taken on the line 4—4 of Figure 3;

Figure 5 is a transverse section taken on the line 5—5 of Figure 3;

Figure 6 is an enlarged detail top plan 60 view of the switch releasing gear wheel and associate parts.

Referring now to the drawings in detail, wherein like numerals of reference are used to indicate corresponding parts throughout 65 the several views, the numeral 1 indicates the switch mechanism housing or casing formed of the usual heavy metal, such as that from which fuse boxes and switch boxes are formed, and hingedly secured to the casing and closing 70 the front side thereof is a cover door 2, while formed through the bottom wall of the casing is a pair of apertures having insulating sleeves 3 fixed therein for the passage of electric wires 4. 75

The top wall of the casing 1 is provided with a longitudinally extending slot arranged at a point between the center and one end of the box and adjacent this slot is formed a smaller coin slot. 80

Mounted within the casing 1 and secured to the rear wall thereof as at 6 is a mechanism supporting frame comprising front and rear walls 7 and 8 respectively, which are in the form of elongated plates as shown, and these plates are in spaced parallel relation and connected together at their left hand ends by the cross portion 9.

Extending to the left from the rear plate 8 is an arm 10 having the free end thereof turned forwardly at right angles as indicated at 11. Mounted upon the cross member 9 is a switch base 12 having the slotted contacts 13 and 14 of the usual construction between which a knife arm 15 connects. The arm 95 15 is pivotally attached to the contact 13 for movement into and out of engagement with the other contact 14. As is clearly shown in Figure 1, the wires 4 are attached to the contacts 13 and 14 and thus when the switch 100

blade 15 is closed, a circuit is completed between the ends of these wires.

Projecting forwardly from the head 16 of the switch blade 15 is a pin 17 to which is attached one end of a contractile spring 18, the other end of which spring is connected to the portion 11 of the member 10. From this it will be readily seen that the spring member 18 acts to normally maintain the switch blade 15 in opened position to break the circuit in which the switch is placed.

Adjacent to and parallel with the rear face of the plate 7, there is arranged a fixed plate 19, carrying the spaced lugs 20 and 21, which maintain this plate in spaced relation to the plate 7. A portion of the upper surface of the lug 20 and the inner surface of the lug 21 are inclined downwardly and to the right.

Slidably supported upon the lugs 20 and 21 between the fixed plate 19 and the frame plate 7 is a switch setting plate indicated generally by the numeral 22. From the left hand end of this plate adjacent to the upper edge thereof, there projects an elongated arm 23, which is preferably formed of insulating material and the free angular end 24 of this arm 23 is provided with a slot, through which the pin 17 of the switch blade projects.

The sliding plate 22 has projecting from the upper edge thereof, at right angles thereto, toward the frame plate 8, the member 25. As shown in Figure 6, this member 25 is arranged between the ends of the plate 22. Secured to the lower face of the member 25 is a substantially U-shaped member or yoke indicated as a whole by the numeral 26, the legs 27 of this U-shaped member being extended downwardly between the frame plate 8 and the fixed plate 19, as is clearly shown in Figure 5.

The sliding plate 22 carries adjacent its right hand end, upon the rear face thereof, the flat lug 28 which, when the plate 22 is moved to the right to close the switch, is adapted to engage the right hand edge of the fixed plate 19. A spring 29 has one end secured to the rear side of the plate 22, as shown in Figure 2, to the left of the member 25, while the other end of the spring is secured to the cross member 9 of the mechanism frame. The normal action of this spring is to pull the plate 22 to the left and also to pull the plate rearwardly toward the fixed frame plate 8, it being shown that the left hand end of the spring is fixed adjacent to the plate 8 and thus a rearward pull is exerted upon the plate 22. When the plate 22 is moved to the right, then this spring 29 acts to draw it over, so that the lug 28 will engage the fixed plate 19, as set forth.

A pair of spaced lugs 30 are formed upon the front face of the sliding plate 22 or between the plate 22 and the plate 7 of the mechanism frame, and these lugs 30 and the lug 20, when the plate 22 is in normal posi-

tion, as shown in Figure 3, are so related as to constitute a support for a coin, such as that indicated in dotted line in this figure, which when resting thereon will not fall between the lugs 20 and 21, but when the plate 22 moves to the right and pressure is removed from the coin, as will be hereinafter described, then the coin is permitted to pass between the lugs 20 and 21 through a passage in the plate 7, indicated at 31, into a pocket 32, which is mounted upon the plate 7 below the passage 31. A finger 33 formed upon the plate 7 guides the coin through the passage 31, instead of allowing the coin to pass through the back of the mechanism frame.

Arranged between the sliding plate 22 and the frame plate 7, is a sliding coin plate 33^a, the rear face of the sliding coin plate having a lug 34 formed thereon, which is arranged to the left of and in a plane between the lugs 30 of the plate 22 and is designed to bear upon the coin resting upon the lug 20 in contact with the lugs 30 to force the entire plate 22 to the right. The upper edge of the plate 33^a is provided with flanges 35 and 36, the flange 35 being arranged at right angles to the face of the plate, whereas the flanges 36 are turned downwardly in spaced relation to the plate 33^a and overlie the upper edge of the frame plate 7, and act as a guide means for the plate 33^a upon this wall. A spring 37 is engaged between the guide flange 36 and the frame plate 7 and normally acts to draw the coin plate 33^a to the left. Pivotedly mounted upon the opposite side of the mechanism wall plate 7 is an operating lever 38, which bears against the flange 35 and by operation on this flange causes the coin plate 33^a to be moved to the right. This lever 38 extends through the longitudinal slot formed in the top wall of the casing 1.

Extending between the frame plates 7 and 8 is a shaft 39, the ends of which extend through longitudinally extending slots 40, so that the shaft is adapted to move horizontally in the same, as will be readily seen. Mounted upon this shaft is a gear wheel 41. Upon the front side of this gear wheel 41 is fixed a pin 42, which, under certain conditions, moves against a stop spring 43, mounted upon the frame plate 7. Upon each of the plates 7 and 8 there is mounted a spring 44, the free ends 45 of which engage the shaft 39, and normally maintains the shaft with its ends in the left hand ends of the slots 40. It will be seen that movement of the gear wheel 41 to the right is against the resistance of these springs 44.

Secured to the rear side of the gear wheel 41 is an angled plate 46, one angle of which has the free edge thereof arranged to move across the front face of the frame plate 8, as is shown in Figure 4.

Hinged to the front edge of the plate, as at 47, is a two armed member indicated as

a whole by the numeral 48, these arms being arranged at acute angular relation, one of them, the arm 49, extending downwardly across the front face of the plate 8, while the arm 50 extends to the front side of the mechanism frame and terminates in a foot portion 51, which is arranged adjacent to and designed to contact with the rear side or face of the right hand portion of the shiftable or sliding plate 22.

Secured to the right hand end of the mechanism frame, between the ends of the frame plates 7 and 8, is a clock mechanism indicated as a whole by the numeral 52. The main spring gear wheel 53 of the clock mechanism is arranged to the right of the gear wheel 41 and, when the device is set so that the switch blade 15 is opened as shown in Figure 3, the gear wheel 41 will be out of connection with the gear 53. When the gear wheel 41 is moved to the right, then the teeth of this wheel will engage with the gear wheel 53 and the wheel 41 will be revolved by this main spring gear wheel.

The main spring shaft 54 is extended through the face of the casing 1 so that a key can be engaged therewith for winding the clock mechanism as needed.

The operation of this device is as follows: A coin of the proper denomination is inserted to the position, as indicated in the dotted lines in Figure 3, being arranged upon the lug 20 between the lug 34 and the lugs 30. After the insertion of the coin, the lever 38 is drawn to the right acting upon the plate 33^a to cause the lug 34 to move to the right against the coin, and continued pressure upon the plate 33^a will cause the sliding plate 22 and coin to move to the right. It will be readily seen that during this operation, the knife blade of the switch will be swung into engagement with the contact 14. As the plate 22 moves to the right, the spring 29 will draw thereon to cause the lug 28 to move rearwardly and engage the fixed plate 19 at the proper time and simultaneous with this movement the yoke 26 will contact with the shaft 39 and move the gear 41 against the tension of the springs 44 into engagement with the gear 53. Due to the engagement of the lug 28 with the fixed plate 19, these gears will be locked in mesh, so that the gear 41 will be revolved by the clock mechanism.

The rearward movement of the right hand end of the plate 22 will also bring this plate into contact with the foot portion 51 of the release or trip mechanism 48 and the elements are so arranged that after the lapse of a predetermined period of time, the trip operating device 46 carried upon the wheel 41 will force its way between the arm 49 and the plate 8, thus causing the two arms 49 and 50 to move forwardly bringing pressure against the right hand end of the plate 22. This pressure will disengage the lug 28 from the plate 19

and the springs 18 and 29 will then come into play to draw the plate 22 to the left and open the switch, as will be readily apparent.

Simultaneous with the above described action, the gear wheel 41 will be moved to the right by the springs 44 as the yoke 26 moves away from the shaft 39 against which it bears when the mechanism is set. The spring 43 is arranged below and to the right of the shaft 39, and the pin 42 rests upon the spring when the switch is opened. During the operation of the device to effect the closing of the switch, the pin 42 travels upwardly away from the spring 43 until the angled plate or trip 46 moves the member 48 far enough to free the plate 22 from engagement with the fixed plate 19. The trip 46 now occupies a position above the spring 43 and to the right of the shaft 39. Due to the position thereof, the trip 46 will by its weight, immediately after the gear 41 is moved out of engagement with the gear 53, move the gear 41 backwardly until the pin 42 again contacts with the spring or stop 43 which limits further turning movement of the gear, with the result that the trip 46 will be returned to and supported in its normal position and the device reset for further operation.

Having thus described my invention what I claim is:

1. In a time controlled coin operated switch of the character described, a switch structure including a swinging knife blade, a sliding switch plate member having connection with said knife blade, a sliding coin plate arranged in side by side relation with the switch plate, means for causing said coin plate and said switch plate to operate simultaneously through a coin connection therebetween for the closing of said switch, means for moving the switch plate laterally to cause it to engage a fixed portion of the structure to maintain the switch in closed position, a time mechanism, and trip means operable by said time mechanism to cause the release of the sliding switch plate to open said switch.

2. In a time controlled switch operating mechanism of the character described, a switch structure, including a swinging knife blade contact, a switch blade control plate, means operating upon said plate to cause the same to normally hold said blade in open circuit position, means for engaging and holding the plate in switch closed position against the action of the holding means acting thereon, a trip mechanism for releasing said plate, a time mechanism, means for establishing connection between said trip mechanism and said time mechanism upon the movement of said plate to a locked switch closing position, a sliding coin plate, means carried by said coin plate and said switch control plate for receiving and holding a coin between the plates, and a pivotally operating lever acting upon the

coin plate and designed to move said switch plate downwardly after the insertion of a coin into said coin holding means.

3. In a time controlled switch mechanism, a switch structure, a sliding element operating to open and close said structure, means for locking the said sliding element in switch closed position, a geared time mechanism, a gear wheel adapted to be moved into mesh with a gear of said time mechanism upon the movement of said sliding element to locking position, a coin controlled means controlling shifting of the sliding element, a trip element, and means carried by said gear wheel for actuating said trip after revolving a predetermined distance to unlock the sliding element for the opening of said switch.

4. In a time controlled switch mechanism, a switch structure, a sliding element operating to open and close said structure, means for locking the said sliding element in switch closed position, a geared time mechanism, a gear wheel adapted to be moved into mesh with a gear of said time mechanism upon the movement of said sliding element to locking position, a coin controlled means controlling the shifting of the sliding element, a trip element, and means carried by said gear wheel for actuating said trip after revolving a predetermined distance to unlock the sliding element for the opening of said switch, and means for disengaging said gear wheel from said time mechanism upon the operation of said sliding means to open the switch.

5. In a switch controlled mechanism of the character described, a switch element including a pivoted contact blade, an elongated shiftable plate having connection with said blade, a fixed element arranged adjacent said plate, a resilient member normally urging said plate toward said fixed element, coin controlled means for shifting said plate to close said switch blade, means for causing locking engagement between said plate and fixed element upon the operation of said plate shifting means, a time mechanism, a laterally movable trip element designed to disengage said plate from said fixed member, after a predetermined period of time, to enable said resilient element to move the plate for the opening of said switch, and means for establishing an operative connection between the trip element and the time mechanism.

6. In a switch controlled mechanism of the character described, a switch element including a pivoted contact blade, an elongated shiftable plate having connection with said blade, a fixed element arranged adjacent said plate, a resilient member normally urging said plate toward said fixed element, coin controlled means for shifting said plate to close said switch blade, means for causing locking engagement between said plate and said fixed element upon the operation of said plate shifting means, a time mechanism, a laterally mov-

able trip element designed to disengage said plate from said fixed member after a predetermined period of time, to enable said resilient element to move the plate for the opening of said switch, and means carried by said shiftable plate for coupling said time mechanism with said trip structure.

7. A coin operated time controlled electric switch, comprising a pair of shiftable plate members arranged in spaced side by side relation, means for coupling said plates for concerted movement by the insertion of a coin therebetween, means for manually actuating one of the plates after coupling the same together, means for coupling the other of said plates to a switch, a lug formed on one face of said other plate for engagement under a fixed element after the said plate has moved a predetermined distance longitudinally to close the switch, a trip trigger comprising a substantially Y-shaped member pivotally mounted at the point of joinder of the divergent arms thereof and arranged to have one of the arms engaged by the switch actuating plate when the same is moved longitudinally to the position described to cause the trigger to be swung laterally, a time mechanism including a main operating gear, a gear member designed to be shifted for engagement with said main gear upon the movement of the last mentioned plate to the position described, and means carried by said shiftable gear for engagement with the other arm of said trip member after rotation a predetermined distance by the gear mechanism, to shift said trip device to cause the first mentioned arm thereof to release the switch controlling plate for reverse longitudinal movement, substantially as set forth.

8. A coin operated time controlled electric switch, comprising a pair of shiftable plate members arranged in spaced side by side relation, means for coupling said plates for concerted movement by the insertion of a coin therebetween, means for manually actuating one of the plates after coupling the same together, means for coupling the other of said plates to a switch, a lug formed on one face of said other plate for engagement under a fixed element after the said plate has moved a predetermined distance longitudinally to close the switch, a trip trigger comprising a substantially Y-shaped member pivotally mounted at the point of joinder of the divergent arms thereof and arranged to have one of the arms engaged by the switch actuating plate when the same is moved longitudinally to the position described to cause the trigger to be swung laterally, a time mechanism including a main operating gear, a gear member designed to be shifted for engagement with said main gear upon the movement of the last mentioned plate to the position described, and means carried by said shiftable gear for engagement with the other arm of

- said trip member after rotation a predetermined distance by the time mechanism, to shift said trip device to cause the first mentioned arm thereof to release the switch controlling plate for reverse longitudinal movement, and means whereby, upon the reverse movement of the switch controlling plate, said shiftable gear will be moved out of engagement with the time mechanism gear. 70
- 10 9. A coin operated time controlled electric switch, comprising a pair of shiftable plate members arranged in spaced side by side relation, means for coupling said plates for concerted movement by the insertion of a coin therebetween, means for manually actuating one of the plates after coupling the same together, means for coupling the other of said plates to a switch, a lug formed on one face of said other plate for engagement under a fixed element after the said plate has moved a predetermined distance longitudinally to close the switch, a trip trigger comprising a substantially Y-shaped member pivotally mounted at the point of joinder of the divergent arms thereof and arranged to have one of the arms engaged by the switch actuating plate when the same is moved longitudinally to the position described to cause the same to be swung laterally, a time mechanism including a main operating gear, a gear member designed to be shifted for engagement with said main gear upon the movement of the last mentioned plate to the position described, and means carried by said shiftable gear for engagement with the other arm of said trip member after rotation a predetermined distance by the time mechanism, to shift said trip device to cause the first mentioned arm thereof to be released for reverse longitudinal movement, and means for reversely rotating said shiftable gear after the actuation of said trip, for moving the trip engaging means carried by the gear away from the trip. 80
- 15 10. A switch controlling mechanism, comprising a time mechanism, an element connected to the switch and adapted to be moved to close the switch, coin controlled means for moving said element, means adapted to latch said element in switch closing position, a trip element for said latching means, trip operating means adapted to be operated by the time mechanism and mounted for movement into and out of engagement with the mechanism, means associated with said switch closing element and trip operating means for moving the latter into engagement with the time mechanism on the closing of the switch, means for moving the trip operating mechanism out of engagement with the time mechanism on the operating of said trip element, and means for opening the switch after the operation of said trip element. 85
- 20 11. A switch controlling mechanism, comprising a time mechanism, an element connected to the switch and adapted to be moved to close the switch, coin controlled means for moving said element, means adapted to latch said element in switch closing position, a trip element for said latching means, trip operating means adapted to be operated by the time mechanism and mounted for movement into and out of engagement with the mechanism, means associated with said switch closing element and trip operating means for moving the latter into engagement with the time mechanism on the closing of the switch, means for moving the trip operating mechanism out of engagement with the time mechanism on the operating of said trip element, and means for opening the switch after the operation of said trip element. 90
- 25 12. A switch controlling mechanism, comprising a time mechanism, an element connected to the switch and adapted to be moved to close the switch, coin controlled means for moving said element, means adapted to latch said element in switch closing position, a trip element for said latching means, trip operating means adapted to be operated by the time mechanism and mounted for movement into and out of engagement with the mechanism, means associated with said switch closing element and trip operating means for moving the latter into engagement with the time mechanism on the closing of the switch, means for moving the trip operating mechanism out of engagement with the time mechanism on the operating of said trip element, and means for opening the switch after the operation of said trip element. 95
